UNITED STATES PATENT OFFICE.

GEORGE ADSIT, OF PATERSON, NEW JERSEY, ASSIGNOR TO BENJAMIN EASTWOOD COMPANY, OF PATERSON, NEW JERSEY, A CORPORATION OF NEW JERSEY.

QUILLING MACHINE.

Application filed October 6, 1921. Serial No. 505,720.

To all whom it may concern:

Be it known that I, GEORGE ADSIT, a citizen of the United States; residing at Paterson, in the county of Passaic and State of New Jersey, have invented certain new and useful Improvements in Quilling Machines, of which the following is a specification.

This invention relates to quilling machines of the kind adapted for winding in layers or series of coils arranged parallel with the axis of winding. The invention consists in certain improvements upon the quilling machine set forth by me in Patent No. 1,063,235.

In the drawings,

Figure 1 is a view showing in side elevation one of the quilling units in operative position on a rail of the frame, which rail and the driving belt appear in section, this view showing an oppositely facing quilling unit and its supporting rail in dotted outline;

Figure 2 is a plan of two quilling units, one appearing in section on approximately the line 2-2, Fig. 1 and one showing the clutch *t*—*x* connected and the other showing said clutch disconnected;

Figure 3 is a front elevation, partly in section, of three quilling units; and

Figure 4 shows a detail.

The driving belt *a* of the machine, only the upper stretch of which is shown, may be supported and driven the same as in the mentioned patent. One of the said rails, *b*, which with the belt extend horizontally and longitudinally of the machine, is arranged at a somewhat higher elevation than the other, *c*, so that the driving whirls for the quilling units that are mounted on the rail *b* may bear against the top, and those for the quilling units that are mounted on the rail *c* may bear against the under side, of said stretch of the belt.

Each quilling unit includes a gear housing of general rectangular form which is secured upon the rail *b* (or *c*), so that all the gear housings on each rail are faced in the same direction and stand close together, and each unit also includes a forwardly projecting structure which in part forms a housing for a certain barrel cam 23.

Each gear housing is a rectangular hollow casting having an integral front wall *d* and a removable rear wall *e*. This casting has inward bottom projections *f* by which, by means of screws *g*, the housing is secured to the rail *b* (or *c*). Each of said forwardly

projecting structures consists of an upright *h* bolted to the front plate *d* and having a bearing at *h'*, a bracket *i* integral with the upright and projecting forwardly and then downwardly and terminating in a bearing *j* opposite bearing *h'*, a half cylindrical shell *k* which is integral with the lower end of upright *h* and the depending end portion of bracket *i*; and a half cylindrical shell *l* which is detachably secured by screws *m* to the shell *k* so as to form a cylindrical housing, the shell *l* having a depressed channel-forming portion *n* at its bottom and at the forward end of such portion a projecting lip *o* provided with a port *p* for supplying the channel with liquid lubricant, as will appear. The shell *m* has a longitudinal slot *m'* at the top.

To the back of plate *e* is secured a U-shaped bracket *q* in which is journaled the shaft *r* equipped with a whirl *s* bearing against the belt and at its forward end with the member *t* of a cone-clutch. Alined with this shaft and journaled in the bearing *u* on plate *d* is the spindle *v* kept against end-wise movement by the collars *w*, one on either side of the bearing *u*, and having splined on its rear end (the spline being indicated at *v'* in Fig. 2) the clutch member *x* to coact with clutch member *t*, there being a collar *y* fixed on the spindle and a spring *z* interposed between such collar and the member *x* to normally urge the latter rearward against member *t*. In a bracket 2 attached to the shell *k* and alined with the spindle is a plunger 3 normally spring-pressed rearward toward the spindle and adapted to coact therewith to removably clamp in place the pin 4 on which the quill windings are formed, all the same as in the mentioned patent. A push-rod 5, having a fork 6 engaged in a peripheral groove 7 in the clutch-member *x* (so that there is slight longitudinal movability of said member relatively to the push-rod) is normally pressed forwardly, so as to disestablish connection between the clutch-members, by a spring 8, but it may be locked back by engagement of its stud 9 with a shoulder 10, all also substantially the same as in the said patent; also, the same as in said patent, it is equipped with an arm 11 having an eccentrically mounted roller 12 to be wiped and rotated by the quill when it reaches a predetermined diameter and so turn the push-rod and thereby release it

105

115

from shoulder 10 so that the consequent dis-establishment of the clutch will stop the spindle.

The thread-traversing mechanism is in its essentials the same as in said patent. That is to say, there are the fork 13 pivoted at 13' in the bracket *i*, the arm 14 pivoted in the fork on the axis 14' (Fig. 3), the thread-guide plate 15 pivoted in the end of said arm 14 on an axis at right angles to 14' and adapted to rest on the package being wound, and a cross-head 16 arranged to travel in a curved slot 17 in the plate 18 attached to bracket *i* and upright *h* and engaged in the slot of fork 13, so that when the cross-head is reciprocated the thread-guide will be reciprocated, the curving of the slot producing a certain desired pitch at the end of the quill as set forth in said patent. The cross-head in the patent is reciprocated by a hook (24) which was capable of up and down motion with the cross-head due to the curvature of the slot corresponding to the above mentioned slot 17' in which the latter moved. In the present construction there is a traveller 19 reciprocatory in a right line on the horizontal rods 20 set in upright *h* and bracket *i*, and this traveller is pivotally connected with the cross-head by a link 21. The traveller has a depending roller 22 reaching through slot *m'* and this runs in the groove 23' of a barrel-cam 23 carried by a shaft 24 rotating on a horizontal axis, the cam being contained in the housing *h* *l* and the shaft being journaled in bearings *j* and *h'*. For the proper lubricating of the groove of this cam I fit in the channel or longitudinal well of the part *n* a wiper of absorbent material, as felt, 25, which upstands sufficiently to bear against the periphery of the cam. Capillary action will take the lubricant (oil) up to the cam in quantity sufficient to lubricate its groove but not sufficient to be thrown off by the cam through slot *m'* and possibly reach the material being wound. On the rear end of shaft 24 is fixed a gear 26 and on spindle *v* is fixed a pinion 27. Respectively meshing with these are the pinion 28 and gear 29 of a transmission member which is journaled on a shaft 30. This shaft is arranged in the U-shaped part 31' of a bracket 31 which is pivoted on shaft 24 and has at its upper end a wing-bolt 32 penetrating an arcuate slot 33' in a bracket 33 projecting from a wall of the gear housing, the shaft being normally held against endwise movement in the bracket by the split hub 28' of the transmission member being clamped to the shaft by a collar 34 secured on said hub by the set-screw 34'. The ratio of the speeds of the spindle and thread-traversing means may be altered by loosening the wing-bolt 32 and the collar 34', withdrawing the shaft 30 endwise through a suitable hole (not shown) in the rear of the gear

housing, removing the transmission member from the top of the gear-housing, substituting for said transmission member another having a gear and pinion of different size, and re-securing said collar and bracket, the latter so that the transmission member meshes with gear 26 and pinion 27.

The employment of a cam rotating on an axis parallel with that of the spindle for effecting reciprocation of the thread-traversing means not only brings about a motion of the parts that is smoother, i. e., less vibratory, than is possible by using a means for reciprocating said traversing means which oscillates on an axis transversely to the spindle, as in the said patent, but it makes it possible to drive said thread-traversing means from the spindle itself and that in turn makes it possible to construct each quilling unit as a self-contained entity, to increase the compactness thereof, and to make the stopping and starting of the means for actuating the thread-traversing means depend directly on the starting and stopping of the spindle, so that special means for starting and stopping the traversing means has not to be taken into account.

I use a barrel cam, specifically, so that, in combination with an absorbent wiper, as 25, bearing against the periphery thereof, there will occur as explained a taking up of lubricant by the cam in just enough quantity to supply the groove 23' without the oil being thrown off by the cam which rotates at considerable velocity.

To change the cam for another it is only necessary to remove the lower shell *l* of its housing and withdraw shaft 24 after releasing the gear 26 thereon.

The gear housing affords not only means for containing the gearing but the main support for each quilling unit, which can be attached to the supporting rail with its drive whirl projecting rearwardly so as to contact with the belt *a* and with the winding mechanism proper and cam housing *h*—*l* projecting forwardly in convenient position with respect to the operator and so as to have ready access for adjustment, repairs or interchange of parts.

Having thus fully described my invention, what I claim as new and desire to secure by Letters Patent is:—

1. In combination, a support, a horizontal rotary spindle journaled therein, a thread-traversing mechanism movable back and forth in said support substantially lengthwise of the spindle, a barrel cam journaled in said support beside and on an axis parallel with the spindle, means to transmit movement from the cam to said mechanism, and a lubricant absorbing wiper extending longitudinally of and bearing against the periphery of the cam.

2. In combination, a support, a horizontal

rotary spindle journaled therein, a thread-traversing mechanism movable back and forth in said support substantially length-wise of the spindle, a barrel cam journaled in said support beside and on an axis parallel with the spindle, means to transmit movement from the cam to said mechanism, said

support having a lubricant well extending longitudinally of the cam, and an absorbent wiper in the well extending longitudinally ¹⁰ of and bearing against the cam.

In testimony whereof I affix my signature.

GEORGE ADSIT.
